OF D 19,602

DESIGN.

—o—
C. C. HISCOE.

WALL AND CEILING COVERING.

No. 19,602.

Patented Jan. 21, 1890.

UNITED STATES PATENT OFFICE.

CHARLES CONSTANTINE HISCOE, OF NEW YORK, N. Y., ASSIGNOR TO
FREDERICK BECK, OF SAME PLACE.

DESIGN FOR A WALL AND CEILING COVERING.

SPECIFICATION forming part of Design No. 19,602, dated January 21, 1890.

Application filed December 26, 1889. Serial No. 335,036. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part thereof.

10 The leading feature of my design represents a mosaic consisting of segmented bands which revolve on their axes to form circular patterns of different sizes, figures 1 and 2. The intervening spaces are filled in with the

same kind of pattern, giving a honeycombed 15 appearance, figure 3.

What I claim is—

A design for a wall and ceiling covering herein shown and described, consisting of a mosaic-like pattern formed by segmented 20 bands which appear to revolve on their axes to form circular bodies of different sizes, the intervening spaces being filled in with the same kind of pattern.

CHARLES CONSTANTINE HISCOE.
